US0D1059453S

(12) **United States Design Patent** (10) **Patent No.:** **US D1,059,453 S**
(45) **Date of Patent:** **** Jan. 28, 2025**

(54) **ROBOT**

(71) Applicant: **Clutterbot, Inc.**, Claymont, DE (US)

(72) Inventors: **Justin David Hamilton**, Wellington (NZ); **Sergio Zapata Velásquez**, Medellín (CO); **Kimberley Atwell**, Wellington (NZ)

(73) Assignee: **Clutterbot, Inc.**, Claymont, DE (US)

(**) Term: **15 Years**

(21) Appl. No.: **29/957,722**

(22) Filed: **Aug. 15, 2024**

(51) LOC (15) Cl. **15-99**

(52) U.S. Cl.

USPC **D15/199**
